(57) **CLAIM**

The ornamental design for a notebook computer having bracket, as shown and described.

DESCRIPTION

FIG. 1 is a perspective view of a notebook computer having bracket showing our new design;

FIG. 2 is another perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a perspective view thereof showing the bracket in the closed status; and,

FIG. 10 is another perspective view thereof showing the bracket in the closed status.

The dashed broken lines illustrate portions of the notebook computer having bracket that form no part of the claimed design.

1 Claim, 8 Drawing Sheets
